UNITED STATES PATENT OFFICE.

ARTHUR B. CARTER, OF BRATTLEBORO, VERMONT.

FILM-REEL AND CASING THEREFOR.

1,304,021.

Specification of Letters Patent.

Patented May 20, 1919.

Application filed April 6, 1917. Serial No. 160,203.

To all whom it may concern:

Be it known that I, ARTHUR B. CARTER, of Brattleboro, in the county of Windham and State of Vermont, have invented certain 5 new and useful Improvements in Film-Reels and Casings Therefor, of which the following is a specification.

It is necessary that motion picture films, being of a highly inflammable character, 10 should be put in metal cases, either for storing or shipping, to protect surrounding property from excessive damage in case of fire, and to protect the film itself. The common method of now doing this is to put each 15 film in a separate can, this can having a cover.

To overcome the expense and inconvenience of this method, it has heretofore been proposed to provide a sectional flanged rim 20 to surround imperforate disks of a motion picture reel, and thus combine the reel and rim to form a casing. Methods of this character as thus far developed are impracticable for several reasons, among which are, 25 the presence of an extraneous locking device, made necessary by a plurality of parts, and the flanges as provided being incapable of standing the wear of constant usage, the projecting flanges becoming loosened by being forced apart to admit the reel, also becoming dented or otherwise damaged so that 30 a flame could easily get through to the film.

The present invention has for its object the overcoming of these difficulties and the 35 production of a construction practicable in every respect, while being economical to manufacture.

Figure 1, is a side elevation of the completed casing, partly broken away, showing 40 in dotted lines the position of the band when opened. Fig. 2, is an end view of the reel member. Fig. 3, is a detail view of the attaching means for the film. Fig. 4, is a partial top view of the completed casing, parts 45 being broken away to facilitate illustration. Fig. 5, is an enlarged section in the plane indicated by the line 5—5 in Fig. 4. Fig. 6, is an enlarged section in the plane indicated by the line 6—6 in Fig. 5.

50 Secured to a hub A, are two imperforate metallic disks B and C, which serve as the sides of the completed casing, hereafter described, as well as the heads of the reel upon which the film is wound. The reel is provided with means for leading the film upon

the hub, shown in detail in Fig. 3, to consist of a web a, one end of which is rolled as shown at b, and the convolutions of which are fastened with a staple c, this roll being passed endwise into a slotted cavity d, in 60 the hub A, before both disks are secured to the hub, and the free end of the web a, leads out through the slot. This free end is long enough to extend beyond the peripheries of the disks B and C, and has secured thereto a 65 clip e, into which the film is placed prior to its being wound upon the reel. The film may be wound up by rotating the reel in either direction.

Fitting around the peripheries of the disks 70 B and C, is a one-piece imperforate metallic band D. This band D, is provided at its edges with specially formed, inwardly opening grooves E and F. At each side the band is provided with a rim a, with an inturned 75 edge b, thereby constituting the grooves E, and F. Each inturned edge is wrapped around a reinforcing wire G. The effect of this wire is not only to strengthen the construction but also to maintain resilience in 80 the band which aids in the effective clasping of the reel and the keeping of the band D, in closed position when so placed.

Coöperating with these grooves E and F, are the outwardly flared peripheral flanges 85 H, of the disks B and C, as shown in Figs. 2 and 6. These flanges are made of the size and shape to fit positively and accurately in the grooves of the band D, when it is brought around them and closed. The film 90 wound upon the reel holds the disks outwardly and accordingly the edges of the disks have to be sprung inwardly slightly when they are fitted into the grooves E and F. This causes the flanges H, to fit securely in 95 the grooves E and F, and insures an effective closure for the preservation of the film, as shown in Fig. 6, the distance between the opposite edges b, of the band rims is less than the distance between the outer edges of 100 the two flanges H, of the disks B, and C. Consequently the band rims are sprung over the flanges and hence resiliently interlocked therewith. This causes the disks to snugly engage the inclosed film and the peripheries 105 of the disk are prevented from spreading apart.

The band D, is also provided at the junction of its two ends with integral overlapping tongues I and J, one on each end of 110

the band and which are in reality continuations of the central body of the band. Located at the bases of the tongues I and J are two rivets K and L, sliding in opposite 5 slots M and N, in the tongues. The lapping of the tongues over and under the band, as illustrated in Fig. 5, forms a friction lock which is adequate in its holding, aided by the resilience of the wires G, as described. 10 This overlapping of the tongues also permits the ends of the grooves and wires to come together as shown in Figs. 1, 4 and 6, and this covers the only hole through which a flame could possibly get. The purpose of 15 the rivets is to keep the tongues from going askew or becoming bent in a way not to be effective.

The friction of the overlapping tongues, and the friction of the flared edges of the 20 disks pressing into the grooves of the band render it practically impossible for this band to be knocked off, or accidentally sprung off, from the reel in the handling of the closed case.

25 To remove the reel from the casing it is only necessary to grip the band near the juncture of its ends and separate the ends to the extent of the grooves M and N, whereupon the reel readily slips out, there being nothing holding it. After the reel is 30 removed the band closes itself by reason of the resilience of the wires. It can then be hung anywhere in the room until needed. To put the reel in the band, it is only necessary to reverse the above procedure, and as 35 a test of whether the reel is properly in place in the band, the user need only see that the ends of the edges of the band meet, as heretofore described, and as shown in 40 Figs. 1 and 4 of the drawings.

I claim—

1. A case for a motion picture film consisting of a motion picture reel comprising a hub having attached at each end an imperforate metallic disk having its periphery outwardly flared, and means for leading a 45 film around said hub, in combination with a one-piece metallic band fitting entirely around the peripheries of said disks, provided with specially formed inwardly opening 50 grooves and a wire on each extreme outer edge forming a reinforcing resilient rim for each side of the band, said grooves coöperating with the flared peripheries of 55 said metallic disks, said band also being provided, at its terminals, with integral tongues which overlap each other, a rivet at the base of each tongue, each tongue having 60 therein a slot which coöperates in sliding engagement with the rivet at the base of the other tongue.

2. A case for a motion picture film consisting of a reel comprising a hub having attached at each end an imperforate disk having 65 its periphery flared, in combination with

a one-piece band fitting entirely around the peripheries of said disks, provided with specially formed inwardly opening grooves and a wire on each extreme outer edge forming a reinforcing resilient rim for each side 70 of the band, said grooves coöperating with the flared peripheries of said disks, said band being provided, at its terminals, with integral tongues which overlap each other, a rivet at the base of each tongue, each tongue 75 having a slot which coöperates in sliding engagement with the rivet at the base of the other tongue.

3. A case for a motion picture film consisting of a reel comprising a hub having attached at each end an imperforate disk having its periphery flared, in combination with a band fitting entirely around the peripheries of said disks, having specially formed grooves and a reinforcing resilient 80 rim for each side of the band, said grooves coöperating with the flared peripheries of said disks, said band also having integral tongues which overlap each other, a rivet at the base of each tongue, each tongue having therein a slot which coöperates in sliding engagement with the rivet at the base of the other tongue.

4. A case for a motion picture film consisting of a reel comprising a hub and side disks, 95 in combination with an integral resilient band fitting entirely around the peripheries of said disks and having therein grooves coöperating with the peripheries of said disks, said band also having at its meeting terminals integral tongues which overlap each other, each tongue having an elongated slot, and a rivet secured near the base of each tongue fitting in the slot of the opposing tongue.

5. A case for a motion-picture film comprising a hub having attached at each end an imperforate metallic disk having at its periphery an outwardly flaring resilient flange, in combination with a one piece imperforate metallic band extending completely around the peripheries of the disks with its ends overlapping and there provided with interengaging sliding connections, said band having at each side a rim 115 with an inturned edge forming a groove to receive the corresponding disk flange, each of said inturned rim edges resiliently interlocking with the adjacent disk flange, and a reinforcing wire at each edge of the band. 120

6. A case for a motion-picture film comprising a hub having attached at each end an imperforate metallic disk having at its periphery an outwardly flaring resilient flange, in combination with a one piece imperforate metallic band extending completely around the peripheries of the disks with its ends overlapping and there provided with interengaging sliding connections, said band having at each side a rim with an in- 125

turned edge forming a groove to receive the corresponding disk flange, each of said in-turned rim edges resiliently interlocking with the adjacent disk flange.

- 5 7. A case for a motion-picture film comprising a hub having attached at each end an imperforate metallic disk having at its periphery an outwardly flaring resilient flange, in combination with a one piece imperforate 10 metallic band extending completely around the peripheries of the disks and having at each side a rim with an in-turned edge forming a groove to receive the corresponding disk flange, each of said in-turned rim edges 15 resiliently interlocking with the adjacent disk flange.

8. A case for a motion-picture film comprising a hub having attached at each end a metallic disk having at its periphery an 20 outwardly flaring resilient flange, in combination with a one piece metallic band extending completely around the peripheries of the disks and having at each side a rim with an in-turned edge forming a groove to 25

receive the corresponding disk flange, each 25 of said in-turned rim edges resiliently interlocking with the adjacent disk flange.

9. A case for a motion-picture film comprising a hub having attached at each end a metallic disk, in combination with a one 30 piece metallic band extending completely around the peripheries of the disks, said band having at each side a rim with an in-turned edge forming a groove to receive the corresponding disk periphery, and a reinforcing wire at each edge of the band. 35

10. A case for a motion-picture film comprising a hub having attached at each end an imperforate metallic disk, in combination with a one piece imperforate metallic band 40 extending completely around the peripheries of the disks with its ends overlapping and there provided with interengaging sliding connections.

In witness whereof, I have hereunto signed my name.

ARTHUR B. CARTER.
